J. SOSS.

HINGE.

APPLICATION FILED AUG. 27, 1919.

1,338,260.

Patented Apr. 27, 1920.

Inventor
Joseph Soss,
By his Attorney
E. J. Galt, Jr.

UNITED STATES PATENT OFFICE.

JOSEPH SOSS, OF NEW YORK, N. Y.

HINGE.

1,338,260.

Specification of Letters Patent.

Patented Apr. 27, 1920.

Application filed August 27, 1919. Serial No. 320,214.

To all whom it may concern:

Be it known that I, JOSEPH Soss, a citizen of the United States, and residing at New York, in the county of New York and State 5 of New York, have invented certain new and useful Improvements in Hinges, of which the following is a specification, such as will enable those skilled in the art to which it appertains to make and use the same.

10 This invention relates to hinges and particularly to what are known as door hinges, and the object thereof is to provide an improved hinge which is simple in construction, comparatively inexpensive and which 15 will be efficient and strong and durable in use; a further object being to provide a hinge of the class specified which is constructed of a plurality of parts stamped from sheet metal and fashioned to the desired 20 shape or form and secured together to form the separate parts or butt members of the hinge; and with these and other objects in view the invention consists in a hinge of the class specified, constructed as hereinafter 25 described and claimed.

The invention described and claimed herein is an improvement on that described and claimed in a prior application filed by me March 8, 1919, Ser. No. 281,358, and is fully 30 disclosed in the following specification, of which the accompanying drawing forms a part, in which the separate parts of my improvement are designated by suitable reference characters in each of the views, and in 35 which:—

Figure 1 is a sectional plan view of my improved hinge showing the same connected with a door frame and door, the section being partially on the line 1—1 of Fig. 2;

40 Fig. 2 a partial section on the line 2—2 of Fig. 1;

Fig. 3 an inside face view of that part of the hinge which is secured to the stationary support; and,

45 Fig. 4 a perspective view of that part of the hinge which is secured to the door or other swinging member.

In Figs. 1 and 2 of the drawing, I have shown at 5 a part of a door frame or other 50 stationary support, and at 6 a door or other swinging member and, in practice, the part 5 is recessed as shown at 7 to receive the part or butt member 8 of the hinge, while the door 6 is recessed at 9 to receive the part or 55 butt member 10 of the hinge.

The part 8 of the hinge is preferably

stamped or fashioned from sheet metal and consists of a front plate 11, which is oblong and rectangular in form and provided adjacent to its upper and lower edges with countersunk apertures 12 through which screws 13 are adapted to pass in securing the part 8 to the door frame 5, as shown in Fig. 3. The central portion of the plate 11 is cut out as shown at 14 to form an irregular-shaped 60 transverse aperture consisting of a large rectangular end portion 15 and a reduced end portion 16. Formed from the material cut out of the part 16 of the aperture and extending inwardly from the top thereof is a 70 spring member 17 which is bent at approximately right angles to the plate 11, as clearly shown in Fig. 2. Secured to the inner face of the plate 11 below the cut-out portion 14 thereof is an L-shaped reinforcing plate 75 member 18, preferably composed of heavier sheet metal than that of the plate 11, as is clearly shown in Fig. 2. The part 19 of the plate member 18 projects at right angles to the plate 11 and is provided with an angularly arranged groove or depression 20 in the top face thereof, as clearly shown in Figs. 1 and 2, which communicates at its inner end with an aperture 21 in said part 19. The groove or depression 20 forms, as 80 85 will be seen, a corresponding projection 22 on the bottom face of the part 19 thus giving said part the required strength in supporting the door in the operation of placing or connecting the part 10 of the hinge with the 90 part 8.

The part 10 of the hinge is made from two similarly formed plate members 23 and 24 which are approximately L-shaped in form, or consist of back plates 25 and approximately hook-shaped arms 26 extending at right angles therefrom. The plates 25 and arms 26 are secured together to form the part 10 by welding, brazing or in any other desired manner. The end portions of the 95 plates 25 are each provided with countersunk screw apertures 27 through which screws 28 are passed in securing the part 10 to the door or other swinging member 6, as illustrated in Fig. 2.

The arms 26 when secured together form a central hook-shaped arm and, in practice, a pin 29 is secured in the free end portion of said arm, part of said pin projecting downwardly and being adapted to operate in 100 the aperture 21 in the plate member 18 or the part 19 thereof.

In the use of this device and after the separate parts 8 and 10 have been secured to the door frame and door, the door may be connected with the door frame by passing the hook-shaped arms of the parts 10 of the hinge, or the free end portions thereof, through the rectangular portion 15 of the cut-out portion 14 of the part 8 with the pin 29 within the groove or depression 20, and when in this position the door is moved inwardly until the pin 29 drops into the aperture 21. It will be understood that in accomplishing the above result that the door 6 will be swung into a position at right angles to the door frame in order to permit of the passage of the hook-shaped arms of the part 10 into the part 8 without coming in contact with the inwardly directed spring member 17 of said part. When the part 10 has been connected with the part 8 in the manner above set out and as indicated in Fig. 2, the door 6 may be swung into its closed position as shown in Figs. 1 and 2, in which operation the spring member 17 operates in connection with the top face of the hook-shaped arm and serves to hold said arm, or the part 10 of the hinge, firmly or against rattling in the part 8, and especially when the door 6 is in a closed position.

The distinctive feature of the construction herein shown and described from that shown and described in the prior application hereinbefore referred to is in the use of a hook-shaped arm on the part 10 of the hinge, of comparatively small transverse dimensions, and the aperture or cut-out portion of the part 8 of correspondingly small dimensions, and the attachment of the reinforcing plate member 18 to the plate 11 to form the support for the part 10 by reason of the fact that the size of the cut-out or apertured portion 14 is insufficient to produce a proper support for the part 10. It will be apparent that the hinge constructed in the manner herein shown and described is designed particularly for use in supporting comparatively light doors but will serve for the same purpose as that of the hinge shown and described in said prior application, and while I have shown certain details of construction for carrying my invention into effect, it will be apparent that I am not necessarily limited to such details, as various changes therein and modifications thereof may be made, within the scope of the appended claims, without departing from the spirit of my invention or sacrificing its advantages.

Having fully described my invention, what I claim as new and desire to secure by Letters Patent, is:—

1. A hinge butt member comprising a

plate which is oblong and rectangular in form and provided centrally with a transverse aperture one end portion of which is deeper or wider than the other, said plate being also provided at the top of the narrower end portion of said aperture with an inwardly directed integral member and at the bottom of said aperture with an angular reinforcing plate which is secured thereto and which projects inwardly therefrom parallel with said member.

2. A hinge butt member comprising a plate, an L-shaped reinforcing plate member secured to one face of said plate, said plate being provided with an apertured portion, a member formed integrally with said plate and extending at an angle thereto, and said reinforcing plate member being provided with a part which extends at an angle to said plate.

3. A hinge butt member comprising a plate, an L-shaped reinforcing plate member secured to one face of said plate and one part of which extends at an angle thereto, said plate being provided with an apertured portion and a member formed integrally with said plate and extending at an angle thereto, and the top face of the inwardly directed part of said plate member being provided with an angularly arranged groove at the inner end of which is an aperture.

4. A hinge butt member comprising a plate which is oblong and rectangular in form and provided centrally with a transverse aperture one end portion of which is tubular or wider than the other, said plate being also provided at the top of the narrower end portion of said aperture with an inwardly directed integral member and at the bottom of said aperture with an angular reinforcing plate which is secured thereto and which projects inwardly therefrom parallel with said member, and another hinge butt plate member provided with a hook-shaped flat arm which projects therefrom at right angles thereto and which is provided on the bottom of its end with a pin, said arm being adapted to be passed through the aperture in the first named plate and to swing in the narrower end portion of said aperture, the wider end portion of said aperture permitting the passage of said pin when the arm is inserted.

In testimony that I claim the foregoing as my invention I have signed my name in presence of the subscribing witnesses this 25th day of August 1919.

JOSEPH SOSS.
